STITCHING FACILITATING APPARATUS

Alexander G. Koenig, Cincinnati, Ohio

Application April 17, 1937, Serial No. 137,575

7 Claims. (Cl. 77—63)

This invention relates to a stitching facilitating apparatus designed primarily to be used in libraries, offices and similar establishments where binding is not practical, but it is to be understood that an apparatus, in accordance with this invention is to be employed in any connection for which it may be found applicable.

The invention has for its object to provide, in a manner as hereinafter set forth an apparatus to facilitate the operation of stitching together in volumes, such items as periodicals, pamphlets, loose sheets, etc., whereby when the items are stitched they will be kept in order and readily accessible when and where binding is not practical.

The invention further aims to provide, in a manner as hereinafter set forth, an apparatus for the purpose referred to which is comparatively simple in its construction and arrangement, strong, durable, compact, readily assembled, conveniently handled, thoroughly efficient in its use and comparatively inexpensive to manufacture.

With the foregoing and other objects in view the invention consists of the novel construction, combination and arrangement of parts as will be more specifically set forth and as illustrated in the accompanying drawings wherein is shown an embodiment of the invention, but it is to be understood that changes, variations and modifications may be resorted to which fall within the scope of the invention as claimed.

In the drawings:

Figure 1 is a front elevation of the apparatus in which is positioned a series of superimposed items to be acted upon in a manner to facilitate the stitching of the items together.

Figure 2 is a side elevation of the structure shown in Figure 1.

Figure 3 is a plan view of the apparatus in horizontal section,

Figure 4 is a section on line 4—4 of Figure 3,

Figure 5 is an exploded view in perspective of the lower clamping plate,

Figure 6 is a perspective view of the combined base and standard element,

Figure 7 is a perspective view of the upper clamping plate,

Figure 8 is a section on line 8—8 of Figure 1,

Figure 9 is a fragmentary view in front elevation of a modified form, and

Figure 10 is a fragmentary view in side elevation of the form shown in Figure 9.

The apparatus shown in Figures 1 to 8 is of the form which includes a manually or hand operat-

ed vertically movable drill, and that shown in Figures 9 and 10 a motor operated drill.

Both forms of the apparatus include a combined base and standard element 11 of a similar construction. The element 11 consists of channel shaped base 12 open at each side and a standard having lengthwise thereof a T-shaped groove opening at its front and at its top. The standard of the form shown in Figure 1 is indicated at 13 and that of the form shown in Figure 9 at 14. The form of the groove in each standard is shown in Figures 6 and 8 and indicated at 14a.

The base 12 consists of a rectangular front member 15, a rectangular back member 16 and a bottom member 17. The members 15, 16 seat at 15 their lower lengthwise edges upon a suitable support not shown. The height of member 16 is greater than that of member 15. The member 16 permanently extends above member 15. The base member 17 merges into or is connected with 20 the rear face of member 15 and the forward face of member 16 above the lower lengthwise edges of members 15, 16. The standard 13 has extending forwardly from the lower end of its forward face an extension 18 which is anchored 25 to the rear face, flush with the lower lengthwise edge of and slightly less in height than that of the rear base member 16. The extension 18 is anchored to member 16 centrally of the rear base of the latter. The forward face of member 16 30 directly above the bottom member 17 is incut to form a square groove 20 which extends from one side to the other side of element 11.

Both forms of the apparatus include a lower clamping plate 21 which is of a size to abut the 35 rear face of base member 15 and to be flush with the sides of element 11. The upper rear marginal portion of plate 21 is rabbeted throughout to form a tongue 22 and a shoulder 23. The thickness of tongue 22 is less than that of the remaining portion of plate 21. The plate 21 is to be removably mounted in superimposed relation with respect to the base member 17 and in abutting relation with respect to the rear face of the base member 15, and when so positioned the 40 groove 20 and tongue 22 coact for slidably connecting base 12 and plate 21 together with the shoulder 23 abutting the forward face of base member 16. The plate 21 in proximity to shoulder 22 is provided with an elongated slot 24 which 45 extends from a point adjacent one side to a point adjacent the other side of the plate. The end walls of slot 24 are rounded. The plate 21 has anchored thereto a pair of spaced aligning vertically disposed clamping screws 25 arranged for 50 55

wardly of and in proximity to the ends of slot 24. Associated with the upper ends of the screws 25 are clamping nuts 26 of the wing type. The purpose of screws 25 and nuts 26 will be presently referred to.

Both forms of apparatus include an upper clamping plate 27 corresponding in width but of less length than plate 21. The rear portion of plate 27 is formed with a rectangular cutout 28 having its side walls 29 positioned in proximity to the side edges of plate 27. The forward or base wall 30 of cutout 28 is positioned between the horizontal median and rear edge of plate 27. Countersunk in the lower face of plate 27 are abutment bars 31 which extend from the front edge and aligned with the rear edge of plate 27. The bars 31 are spaced from each other and are arranged inwardly of and spaced from the side walls 29 of the cutout 28. The distance between the bars 31 is greater than the distance between a bar and a side wall of the cutout. The bars extend across the bottom of cutout 28 and are anchored to plate 27 by the holdfast means 32. The plate 27 is formed with a pair of spaced aligned openings 32a arranged forwardly of and in proximity to the side walls 29 of the cutout 28.

The apparatus shown by Figures 1 to 8 includes a T-shaped vertically movable slide 33 mounted in the groove 14a of the standard 13. The slide 33 has its head designated 34 and its stem 35. The latter extends forwardly from the front face of standard 13. The standard 13 is formed at one side with a hollow lateral extension 36 which has mounted therein and extended therefrom a spring controlled latching device 37 for releasably engaging in a pocket 38 (Figure 8) formed in a side edge of head 34 of the slide 33. The pocket 38 is arranged in slide 33 in proximity to the upper end of the latter. When the device 37 is in engagement with the wall of pocket 38 the slide 33 is latched in its upper position.

Carried by slide 33 forwardly of the latter is a hand operated drill 39 which is secured to the stem 35 by the attaching devices 40.

The apparatus shown by Figures 9 and 10 includes a T-shaped vertically movable slide 41 which is mounted in the groove 14a of the standard 14. The slide 41 has its head designated at 42 and its stem at 43. The latter extends forwardly from the front face of standard 14. Secured to the front of stem 43 is an electrical motor 44 which is to be connected with a source of supply not shown. Secured to one side of the head 42 of the slide 41 is a laterally disposed arm 45 from which depends an angle-shaped elevating and lowering bar 46 for slide 41. The bar 46 at its lower end is pivotally connected, as at 47, to an upstanding operating lever 48. The lower end of lever 48 is pivotally connected, as at 49 to one side of standard 14. Carried by and operated from motor 44 is a depending drill 50.

The form shown by Figures 9 and 10 including a latching means 51 is of the same form and arrangement as latching means 37.

With reference to Figures 1, 2, 9, and 10 a stack 52 of items are shown in position to be acted upon by the apparatus. The stack is mounted on the lower clamping plate and positioned against the forward face of the rear member 16 of base 12. The upper clamping plate is then mounted on the stack 52, and when so mounted the screws 25 extend through the openings 32a. The nuts 26 are then engaged with the screws 25 and secured to bind against the plate 27 whereby the stack is tightly clamped be-

tween the plates 21, 27. The lower plate 21 constitutes a sliding platform. The rear base member 16 forms a guide. By moving the plate 21 horizontally and either drill thrown into operation, the necessary number of spaced holes at the desired points may be drilled in the stack 52, for the passage of stitching or a binder to secure the items of the stack together. The slot in plate 21 and the cutout in plate 27 provide superposed clearances for the tool of the drill. After the stack has been provided with holes, the plate 21 is removed from the base, with the stack tightly clamped and while clamped between plates 21, 27 the items of the stack are secured together by stitching. The slot in plate 21 and cutout in plate 27 provide clearance for the stitching operation.

What I claim is:

1. In an apparatus for facilitating stitching for the purpose set forth, a channel-shaped base open at each side and including a front and a rear wall, a standard secured to the rear wall and formed with a groove opening at its front face, a controllable slide adapted to be connected to a drilling means, said slide mounted in the groove of the standard, a lower clamping plate 25 removably mounted in the base for receiving the work to be acted upon, said plate and rear wall having oppositely disposed interengaging rabbets for slidably connecting the plate to the base, an upper clamping plate for mounting on the work, means co-acting with said plates for clamping the work between the plates, said lower plate capable of being shifted relative to the base to position successive points of the work to be acted upon by said drilling means and to remove the work from the base while clamped between the plates, and said plates being formed rearwardly of said coacting means with clearances for the drilling means.

2. In an apparatus for facilitating stitching for the purpose set forth, a channel-shaped base open at each side and including a front and a rear wall, said rear wall being of greater height than said front wall, a lower clamping plate removably mounted in the base for receiving the work to be acted upon, said rear wall and lower plate having coacting means for slidably connecting said plate to the base, a standard having its lower end anchored to said rear wall and being formed with a groove opening at the front thereof, a vertically movable controllable drilling structure slidably mounted in the groove of the standard and over-hanging the base for action upon the work, an upper clamping plate for mounting on the work, means coacting with said plate for clamping the work therebetween, said lower plate capable of being shifted relative to the base to position successive points of the work to be acted upon by the drilling structure and to remove the work while clamped between the plates from said base, said upper plate being formed in its rear edge with a U-shaped cutout, said upper plate being formed in proximity to its rear edge with an elongated slot aligning with said cutout, said cutout and slot providing clearances for said drilling means.

3. In an apparatus for facilitating stitching for the purpose set forth, a channel-shaped base open at each side and including a front and a rear wall, a standard secured at its lower end to said rear wall and being formed with a T-shaped groove opening at its top and at its front, a controllable vertically movable T-shaped slide mounted in said groove and adapted to carry a drilling means in overhanging relation with respect to the work

to be acted upon, upper and lower plates, said plates having coacting interengaging means in proximity to their rear edges for clamping the work therebetween, said rear wall and upper plates having coacting interengaging means for slidably connecting the lower plate to the base, said lower plate capable of being shifted relative to the base to position successive points of the work to be acted upon by the drilling means and 10 to remove the work while being clamped between the plates from said base, said upper plate having its rear edge formed with a clearance for said drilling means; and said lower plate being formed in proximity to its rear edge with a clearance 15 for said drilling means.

4. An apparatus for facilitating stitching for the purpose set forth, a removable and slidably mounted lower clamping plate for receiving the work to be acted upon, said plate including upwardly extending clamping screws in proximity to its rear edge, an upper clamping plate for mounting on the work carried by the lower clamping plate and formed in proximity to its rear edge with openings for the passage of said screws, 20 clamping nuts mounted on said screws and coacting with said upper plate for clamping the work between the plates, said lower plate being formed in proximity to its rear edge and rearwardly of said screw with an elongated slot, said upper plate having its rear edge formed with a cutout aligning with said slot, said cutout and slot providing respectively upper and lower clearances for a tool which is to operate on the work, a support for said lower plate, said support and 25 lower plate having coacting means for slidably connecting the lower plate to the support, a vertically adjustable slide for the tool which is to operate on the work, a grooved standard secured to the support and in which said slide is mounted, 30 and a latching means carried by the standard for the slide.

5. In an apparatus for facilitating stitching for the purpose set forth, a channel-shaped base open at each side and including front and rear walls, a standard secured to said rear wall and formed lengthwise thereof with a groove opening at its front face, a lower clamping plate removably mounted within the base for receiving the work to be acted upon, said plate and rear wall 45 having coacting interengaging means for slidably connecting said plate to the base, a vertically movable slide for carrying a tool to operate on the work, said slide being mounted in the groove of said standard, means coacting with said plates 50 for clamping the work therebetween, said lower

plate capable of being shifted relative to the base to position successive points of the work to be acted upon by the tool and to remove the work while clamped between the plates from said base, and latching means carried by the standard for 5 said slide.

6. In an apparatus for facilitating stitching for the purpose set forth, a channel-shaped base open at each side and including front and rear walls, a standard secured to said rear wall and formed 10 lengthwise thereof with a groove opening at its front face, a lower clamping plate removably mounted within the base for receiving the work to be acted upon, said plate and rear wall having coacting interengaging means for slidably 15 connecting said plate to the base, a vertically movable slide for carrying a tool to operate on the work, said slide being mounted in the groove of said standard, means coacting with said plates for clamping the work therebetween, said lower 20 plate capable of being shifted relative to the base to position successive points of the work to be acted upon by the tool and to remove the work while clamped between the plates from said base, latching means carried by the standard for 25 said slide, and said upper plate having its rear edge cut out and said lower plate being formed in proximity to its rear edge with a slot, said cut-out and slot forming upper and lower clearances for the tool carried by the slide. 30

7. In an apparatus for facilitating stitching for the purpose set forth, a base including a front and rear wall, a standard secured to and extending upwardly from said rear wall, a lower clamping plate removably mounted within the base for 35 receiving the work to be acted upon, said rear wall and plate having coacting interengaging means slidably connecting the plate to the base, a vertically movable slide connected with the standard and adapted to carry a tool for action 40 upon the work, an upper clamping plate for mounting on the work, means in proximity to the rear edges of said plates and coacting with said plates for clamping the work between the plates, said lower plate being formed with a slot 45 rearwardly of said clamping means, said upper clamping plate having its rear edge cut out, said slot and cutout forming clearances for the tool, and said lower plate capable of being shifted relative to the base to position successive points 50 of the work to be acted upon by said drilling means and to remove the work while clamped between the plates to said base. 55

ALEXANDER G. KOENIG. 55
